UNITED STATES PATENT OFFICE.

AUGUST BREMER, OF HALLE-ON-THE-SAALE, GERMANY.

HANGER DEVICE FOR SUPPORTING BOARDING OR PLANKING ON IRON GIRDERS.

SPECIFICATION forming part of Letters Patent No. 635,122, dated October 17, 1899.

Application filed March 28, 1899. Serial No. 710,809. (No model.)

To all whom it may concern:

Be it known that I, AUGUST BREMER, a subject of the Emperor of Germany, residing at Halle-on-the-Saale, Germany, have invented 5 a certain new and useful Improved Hanger Device for Supporting Boarding or Planking on Iron Girders, of which the following is a full, clear, and exact description.

The present invention consists of a hanger 10 device for supporting boarding or planking on iron girders, where such may be temporarily required.

In order to render the present specification more easily intelligible, reference is had to the 15 accompanying drawings, in which similar letters of reference denote similar parts throughout the several views.

Figure 1 is a side elevation of the hanger attached or hung onto a girder; Fig. 2, a similar elevation of the same hanger applied to a 20 girder of smaller cross-section; Fig. 3, a front elevation of the hanger; Fig. 4, a section showing the application of a pair of hangers to support planking on two girders; Fig. 5, a section 25 on line N N of Fig. 4; Fig. 6, a plan showing the application of two hangers to support an arched planking, and Fig. 7 a sectional elevation of the device illustrated by Fig. 6.

The hanger consists of the shank *a*, having 30 a hook *b*, said hook being bent around at an obtuse angle to the said shank, in order to prevent it from lying on the flange of the girder with its whole surface, which would cause breakage if the hanger were very heavily loaded and the form of the girder were such 35 that it did not lie evenly on the whole surface. From the lower part of the shank *a* a fulcrum-arm *t* extends, being arranged at an acute angle to the said shank and adapted to 40 press with its upper end against the lower

side of the girder. At the opposite side of the shank to that at which the arm *t* is provided are arranged a pair of lugs *g g*, in which a carrier-bar *p* is mounted to turn, said bar serving to support the planking.

The application of the device will be evident from Figs. 4 to 7. In Figs. 4 and 5 two hangers are employed, one at either side of the beam *k*, which may be supported on wedges inserted between the carrier-bar and the said beam, and thus the planking supported between the girders *h h*. When the planking is to be removed, the carrier-bars may be simply turned on their hinges and the whole planking allowed to fall down. In Figs. 6 and 55 7 arched planking is illustrated, also supported by means of two hangers and a templet *d*.

The advantage of the present hanger is that the same may be conveniently applied to girders of any cross-section.

I claim as my invention—

A hanger for supporting planking on girders of any cross-section, which consists of a shank having an upper hook bent around at an obtuse angle to the said shank, a fulcrum-arm 65 extending from the lower part of the shank at an acute angle to the same upwardly and adapted to engage the under surface of the girder and a carrier-arm pivotally connected to the opposite side of the said shank 70 at the lower part of the same to turn in a horizontal plane in the manner and for the purpose substantially as described.

In witness whereof I have hereunto set my hand in presence of two witnesses.

AUGUST BREMER.
